UNITED STATES PATENT OFFICE.

ERNEST L. PATTEN, OF NEW HAVEN, CONNECTICUT, ASSIGNOR TO L. CANDEE & COMPANY, OF NEW HAVEN, CONNECTICUT, A CORPORATION OF CONNECTICUT.

SHOE-TRIMMING MACHINE.

Application filed July 6, 1923. Serial No. 649,849.

To all whom it may concern:

Be it known that I, ERNEST L. PATTEN, a citizen of the United States, residing at New Haven, county of New Haven, and 5 State of Connecticut, have invented certain new and useful Improvements in a Shoe-Trimming Machine, of which the following is a full, clear, and exact description.

This invention relates to a trimming machine, more particularly to a machine for trimming the tops of rubber shoes.

In the usual method of making rubber shoes a rubberized elastic lining, such as stockinette, is joined into a bag-like form, 10 drawn down over the last until properly conformed thereto, and the bottom edges fastened over on an insole. The various toe, heel, and other reinforcements are then applied, the rubber upper superposed on the lining, the outsole rolled on, and a thickened bead of rubber laid around the upper on a line forming the top of the shoe. The shoe is then varnished by dipping and cured. It is not practicable for a number of reasons 15 to make the lining of the exact size as found in the finished shoe. In the first place the operator in lasting the lining stretches and pulls it to conform it to the shape of the last, and hence if the upper part of the lining were cut to the finished size it would not have its upper edge symmetrically disposed after such pulling and stretching. 20 Another reason is that in the varnishing operation, which as before stated is accomplished by dipping, it is not practicable to prevent the varnish from flowing above the top line of the shoe as formed by the rubber bead, hence the varnish would get on the last and also down inside of the shoe, 25 thereby ruining it. The lining, therefore, as applied to the shoe extends upwardly on the last some little distance above the top of the finished shoe as defined by the bead. After curing it therefore becomes necessary to trim away the projecting portion of the lining. As far as I am aware this operation has ordinarily been performed by hand, the operator using a sharp knife and with a draw cut guiding it around 30 the upper edge of the shoe adjacent the bead. There are a number of objections to this manner of trimming the shoe. As it must be done while the shoe is still on the last, the use of the last is therefore re-

quired throughout the making of the shoe, 55 since the trimming is the final operation. In a footwear factory a large amount of capital is tied up in lasts, owing to the large variety of sizes and styles used. Hence it is desirable to reduce as much as possible the operations requiring the use of lasts. Another objection is that after a short time the last becomes badly scored from the trimming knife. Still another objection is that as long as the shoes are on 60 lasts, racks are required for their handling and transportation from one part of the factory to another. A further objection is that a relatively skilled operator is required to perform the work; and even then 65 a considerable percentage of the shoes is ruined by reason of the knife cutting through the top head. Moreover, owing to the draw cut a very sharp knife is required to prevent pulling and distortion of the 70 upper as the operator moves the knife around the top edge. Should the operator's knife veer upwardly instead of downwardly through the bead a fin of lining will be left on the shoe edge at that point, and 75 if the operator then attempts to cut this fin by retracting the knife it is difficult to prevent the upper from pulling and stretching unless the knife is very sharp. Finally, even in the hands of a skilled operator the 80 trimming operation is relatively slow.

An object of my invention is to speed up the production of rubber footwear.

Another object is to lessen the number of operations requiring lasts and racks.

Still another object is to avoid injury to the last.

A further object is to obviate the production of seconds or damaged articles in the shoe top trimming process.

A still further object is to provide an improved trimming machine for rubber shoe tops and for similar purposes.

For a detailed disclosure of the invention reference is had to the accompanying specification and drawings, in which latter:

Fig. 1 is a side elevation of my invention shown as mounted on a truck for portability.

Fig. 2 is a plan of the machine proper.

Fig. 3 is a vertical longitudinal section,

Fig. 4 is a front elevation with parts broken away,

Fig. 5 is a sectional detail,

Fig. 6 is a fragmentary front elevation, and

Fig. 7 is a side view of a finished shoe before removal from the last.

Referring to the drawings the numeral 1 designates a truck provided with an adjustable seat 2 for the operator and with a hollow column 3 having communication with a scrap hopper 4, the side of the column 10 being provided with a door 5 for the removal of the scrap. Secured to the top of the column is the frame 6 of the machine, having mounted at one end thereof an electric motor 7, the shaft 8 of which is connected by a flexible coupling 9 with the main shaft 10 of the machine. It is obvious, however, that any other suitable drive may be substituted for the motor 7. The main shaft 10 is carried on bearings 11 and 12 20 in the frame, and at its front end has connected thereto a crank pin 13 on the outer end of which is pivotally mounted a link 14. The lower end of the link 14 is pivotally mounted on a pin 15 rigidly secured 25 in a cutter slide 16, the latter having a dovetail slide connection with the frame of the machine as shown in Figs. 2, 3, and 4. Adjustably mounted in the lower end of the slide by a dovetail joint is a cutter blade 30 17 having at its lower end the inclined cutting edge 18. Adjacent its lower end the slide 16 is cut away at one side as shown at 16' in Fig. 4, for a purpose to be later explained. In 35 order to secure the blade in adjusted position a recess 19 is cut in one side of the slide 16 and in this recess fits the head 20 of one member of a clamping element, which member extends through the slide as shown 40 at 21 and has threadedly secured to its opposite end a second clamping member 22 adapted to engage the side of the slide 16. It will be seen that by tightening the clamping member 22 the head 20 will be drawn 45 against the blade 17 to hold it in position.

Secured on the main shaft 10 is a helical gear 23 meshing with a similar gear 24 carried by the upper end of a short vertical shaft 25 mounted in bearings 26 and 27 in 50 the frame. Secured on the lower end of shaft 25 is a worm 28 meshing with a worm wheel 29 secured to a shaft 30 mounted in the lower part of the frame. Adjacent its forward end the shaft 30 has secured thereon 55 a knurled feed roll 31 and slightly spaced therefrom a rotary cutter 32, which latter is also knurled over the greater part of its periphery to assist in the feed, but on its inner portion adjacent its cutting edge is 60 smooth as shown at 33. Secured to the frame is a deflector 34 for lint, thread, etc., which deflector extends up between the feed roll 31 and rotary cutter 32 and surrounds 65 the shaft 30 but is independent thereof. A portion of this deflector is cut away as

shown at 34' to provide clearance for the blade 17 and in order that any lint or thread gathering in the space between the feed roll and cutter may be thrown downwardly and out by the movement of the parts.

Cooperating with the feed roll 31 is an idler feed roll 35 carried on a bent arm 36 pivoted to the frame at 37, the free end of the arm being resiliently drawn upward by the adjustable coil spring 38. Disposed in front of the cutter blade is a guard and guide 39 mounted on an arm 40, the rear end of which is vertically disposed and threaded and adjustably connected to the frame by means of the thumb nuts 41 and 42. Adjacent its lower edge and at one side the guard 39 is preferably thickened as shown at 39' to guard the side of the reciprocating cutter blade 17 (Fig. 6). In the present instance this thickened portion is formed by riveting a small piece of metal to the guard, but it is obvious that it may be made integral therewith or formed in any other desired manner. The cut away portion 16' of slide 16 allows the latter to reciprocate without obstruction by the thickened portion 39'. Attached to the frame of the machine at 43 and extending across the face of the guard is a spring clip 44 for maintaining the guard in operative position.

In operation the blade 17 is properly adjusted to cooperate with the edge of the rotary cutter 32, and the guard and guide 39 is vertically adjusted so that its lower edge is spaced from the periphery of the rotary cutter 32 adjacent its cutting edge just sufficiently to allow the projecting or superfluous portion of the shoe lining to pass beneath the same and into the path of the reciprocating blade 17, but it is kept close enough to the rotary cutter 32 to prevent the thickened top bead of the shoe from passing beneath the guard. The lasts are of course removed from the shoes when cured and the latter then brought to the operator, who after starting the machine passes a portion of the projecting shoe lining 45 beneath the guard 39 and idler feed roll 35 until the top bead 46 of the shoe 47 bears against the guard. Using the guard as a guide the operator feeds the shoe along, keeping the bead of the shoe at all times pressed against the guard 39. As the guard is of relatively thin material with a thin bottom edge, and as it is disposed directly against the reciprocating blade 17, the latter in cooperation with the rotary cutter 32 trims off the superfluous lining closely adjacent the top edge of the shoe as defined by the bead 46. Owing to the small size of the blade 17 the operator can readily feed the shoe top so as to easily cut around any very sharp curves such as those formed by the top of a storm rubber. Should the operator by inadvertence fail to keep the shoe bead pressed against the guard

39, so that a fin of lining is left on the shoe, this can readily be removed by merely retracting the shoe and again feeding the superfluous portion past the cutting point while 5 keeping the bead against the guard 39. Since the blade 17 operates perpendicularly to the work there is no tendency to draw or pull the shoe upper and the latter can therefore be very accurately trimmed. As it is 10 impossible to feed the top bead of the shoe beneath the guard 39 when properly adjusted the spoiling of shoes by inaccurate cutting through the bead is entirely obviated. It will also be seen that scoring of the last 15 is prevented and free use can also be made of metal lasts when desired, since the lasts are removed before trimming. Owing to this removal of the lasts before the trimming 20 operation, it will be seen that the number of operations requiring the use of a last is reduced by one. For the same reason the number of operations requiring the use of a rack is also reduced by one.

While a specific embodiment of the invention has been shown and described, it is obvious that with the present disclosure numerous modifications and other uses will suggest themselves, and it is not desired to limit the invention otherwise than as set 30 forth in the appended claims.

Having thus described my invention, what I claim and desire to protect by Letters Patent is:

1. An article trimming machine comprising cooperating reciprocable and rotary cutting elements, means for actuating the same, a feed roll rotatable with said rotary cutting element and spaced therefrom for the passage of said reciprocating element, 35 and a guard covering said last element and spaced from the rotary one for the passage of the material to be trimmed.

2. An article trimming machine comprising a feed roll and a rotary cutting element mounted in spaced relation on a shaft, a reciprocable cutting element movable into and out of said space and cooperating with the edge of said rotatable element, and a refuse

deflector disposed in said space below said reciprocable cutting element. 50

3. A shoe trimming machine comprising a feed roll and a rotary cutting element mounted in spaced relation on a shaft, a reciprocable cutting element movable into and out of said space and cooperating with the edge of said rotatable element, and a thin edge guard covering said reciprocable element and adjustably spaced from the edge of said rotatable element. 55

4. A shoe trimming machine comprising a feed roll and a rotary cutting element mounted in spaced relation on a shaft, a reciprocable cutting element movable into and out of said space and cooperating with the edge of said rotatable element, a guard and 60 guide cooperating with said elements for preventing the cutting of the shoe proper, and a refuse deflector disposed in said space below said reciprocable element. 65

5. A rubber shoe top trimming machine 70 comprising a substantially cylindrical rotary cutting element having one end formed as a cutting edge, a feed roll rotatable therewith and spaced from said edge, a reciprocable cutting element cooperating with said 75 edge and movable in said space, a top bead guard and guide spaced above said edge closely adjacent the cutting point, and resilient means for maintaining said guard in position. 80

6. A rubber shoe top trimming machine comprising driven and idler feed rolls, a rotary cutting element coaxial with said driven roll but slightly spaced therefrom, a reciprocable cutting element movable in said 85 space in shearing relation with said rotary cutting element, and a top bead guide disposed adjacent the cutting point and spaced from said rotary cutting element a distance less than the thickness of the shoe top at the 90 bead.

Signed at New Haven, in the county of New Haven and State of Connecticut, this 2nd day of July, 1923.

ERNEST L. PATTEN.
